UNITED STATES PATENT OFFICE.

WILLIAM J. BURNETT, OF GLENSIDE, PENNSYLVANIA, ASSIGNOR TO BEAUMONT MANUFACTURING COMPANY, OF PHILADELPHIA, PENNSYLVANIA, A CORPORATION OF NEW JERSEY.

MECHANISM FOR ACTUATING THE GATES OF GRAVITY DISCHARGE HOPPERS.

Application filed December 9, 1926. Serial No. 153,533.

This invention relates to mechanism for actuating the gates of gravity discharge hoppers, and more particularly to the longitudinally movable type ordinarily used, 5 for example, with the ash hoppers in power houses. Such gates, on account of their comparatively large size and the weight of the ashes normally resting thereon, require the application of considerable effort to open 10 and close them, especially when grouped in gangs for simultaneous operation.

The main object of the present invention is to enable actuation of such gates by use 15 of power instead of manually as has generally been the case heretofore; and in this connection it is my aim to provide a very efficient and reliable mechanism that will accomplish the desired results with extreme rapidity, to the avoidance of any possibility 20 of gate binding, and which, when once started, will come automatically to rest when the gates are moved to the full extent in either direction.

In connection with systems entailing the 25 use of gates grouped in multiple, it is a further object of my invention to enable selective actuation of any desired group of the gates to the exclusion of others with employment of but a single prime mover.

Still further objects and attendant advantages of my invention will be readily apparent from the detailed description which follows.

With reference to the drawings, Fig. I 35 is a partial vertical sectional view of a typical power house showing its ash hoppers equipped with gate operating mechanism embodying my invention.

Fig. II is a fragmentary sectional elevation of the organization more or less diagrammatically represented and taken as indicated by the arrows II—II in Fig. I.

Fig. III is a cross sectional view through one of the ash hoppers taken as indicated 45 by the arrows III—III in Fig. I.

Fig. IV is a local detail sectional view taken as indicated by the arrows IV—IV in Fig. II, showing one of the timing devices controlling automatic stoppage of the motor; and.

Fig. V a plan sectional view taken as indicated by the arrows V—V in Figs. I and II.

The organization chosen for the purposes of illustration herein involves the use of two 55 boilers which are designated 10 and 11 in Figs. II and V, and wherefrom the ashes are received in underlying hoppers 12, 13 respectively. The side walls of these hoppers 12, 13 are convergently sloped—as 60 shown in Fig. III—to promote gravity discharge through bottom outlets 14, 14 set apart, in both instances, by central dividing ridges 15 extending transversely of said hoppers. The outlets 14 are controlled by gates 65 16 that are equipped with rollers 17 adapted to run along guide rails 18, the latter being suspended at one end by brackets 19 depending from the respective hoppers 12, 13, and at the other end, by the substructure supporting the boilers 10, 11. As shown in Fig. I, the ashes are conducted to the hoppers 12, 13 by endless conveyors whereof one is conventionally represented at 20; and nozzles 21 are provided for spraying water into 70 the ashes to quench them after customary practice, said nozzles being supplied, through piping 22, from a suitable source not illustrated. For the purpose of drainage, each gate 16 is formed with a gutter 23 that extends crosswise of the back end thereof as well as continuously along opposite sides; and individual stationary troughs 24 (Figs. I and V) receive the spill which is conducted off through drain conduits 25. When the 75 gates 16 are opened, the ashes are released to drop from the hoppers 12, 13 into a waiting car or other portable receptacle 26 in the clear space beneath the boilers 10, 11.

The description thus far given is that of a 80 typical ash disposal system such as commonly employed in modern power houses, and, per se, forms no part of the present invention which is concerned only with the gate actuating mechanism now about to be 85 set forth. This mechanism includes an electric motor M which is shown as housed for protection against dust, in a pit 27 beneath the main floor 28 of the power house, and adapted to drive, through a connection 29 with interposed flexible couplings 30, speed reduction gearing 31 housed within a casing 32—all located in the interval between the boilers 10, 11—as shown in Figs. II and V. The worm wheel 33 of the gearing 31, just 105 referred to, is affixed to a shaft 34 that ex-

tends to the exterior through appropriate bearings at opposite sides of the casing 32, see Fig. V, and carries on its protruding ends, clutch members 36, 37 adapted to co-5 operate, respectively, with opposing clutch members 38, 39 on the contiguous ends of aligned shaft sections 40, 41 that are common to the hoppers 12, 13 of the two boilers 10, 11. On these shaft sections 40, 41 are 10 secured, in proper spaced relation, spur pinions 42 that mesh with toothed racks 43 along opposite side edges of the several gates 16. The clutch members 38, 39 are splined to, but slidable on the shaft sections 15 40, 41, and arranged for selective actuation by pivoted yoke arms 44, 45 that are respectively coupled, by means of links 46, 47, with hand levers 48, 49 located for convenience of access at remote ends of the boilers 20 10, 11, see Fig. II. Suitable means such as ratchet sections conventionally shown at 50, may be provided to lock the levers 48, 49 in shifted positions to hold the companion clutch members 38, 36 or 39, 37 engaged. A 25 flexible chain connection 51 between the contiguous ends of the links 46, 47 insures against both clutches 36, 38 and 37, 39 being engaged at the same time yet permitting independent disengagement of either, as will 30 be readily apparent from Fig. II. The motor M is controlled for rotation in opposite directions by a standard type of drum reverse switch conventionally indicated at S in Fig. I, so that either of the two groups of 35 gates 16 may be opened or closed by first clutching the corresponding shaft sections 40, 41 with the speed reduction gearing 31, through selective shifting of the hand levers 48, 49, and thereafter starting the motor M 40 rotating in the proper direction by means of the control switch S.

In order to stop the motor M automatically when the gates 16 reach the limit of movement in either direction, I equip the 45 shaft sections 40, 41 with rotary timing cams 51, which, as shown in Fig. IV, have rises 52 adapted to trip limit—switches 53, 54 in accordance with the direction of rotation—and in a manner—which will be obvious in 50 view of the legends associated with the illustration last referred to. The limit switches 53, 54 may be of any approved commercial type, and the same—as well as the control switch S—interposed in the motor circuit in 55 a manner well known to artisans skilled in the installation of such devices. To protect the mechanism against injury likely to result from over-running of the motor M, I preferably employ, as an additional adjunct 60 in association with said motor, a magnetic brake device of standard construction dia-

grammatically indicated at 55 in Figs. I and V of the drawings.

Although I have herein described the gate actuating mechanism of my invention as being particularly useful with ash disposal systems of power houses, it may obviously be employed, with advantages equal to those pointed out, in installations of a generally similar sort for handling and storing materials other than ashes, and the appended claims are therefore to be construed with this broader aspect in mind.

Having thus described my invention, I claim:

1. Mechanism for actuating the gates of a multiplicity of gravity discharge hoppers including an individual shaft for each hopper and equipped with gear pinions in mesh with toothed racks on the associated gates, speed-reduction mechanism interposed between the contiguous shaft ends, an electric motor adapted to drive the speed-reduction mechanism in opposite directions to open and close the gates, and means whereby the respective shafts may be selectively coupled with said speed-reduction mechanism.

2. Mechanism for actuating grouped gates of a pair of gravity discharge hoppers arranged side by side, comprising aligned shaft sections one associated with each group of the gates and each carrying gear pinions adapted to mesh with toothed racks on said gates, speed reduction gearing in the interval between the shaft sections and co-ordinated to an electric motor—adapted for reverse rotation—by interposed flexible couplings, and control means enabling selective clutching of the shaft sections with the speed reduction gearing.

3. Mechanism for actuating grouped gates of a pair of gravity discharge hoppers arranged side by side, comprising aligned shaft sections one associated with each group of the gates and each carrying gear pinions adapted to mesh with toothed racks on said gates, speed-reduction gearing in the interval between the shaft sections co-ordinated to an electric motor adapted for reverse rotation with interposition of flexible couplings, and control means enabling selective clutching of the shaft sections with the speed-reduction gearing, said control means including separate hand levers with a flexible connector therebetween to insure un-clutching of one of said shafts incident to clutching of the other.

In testimony whereof, I have hereunto signed my name at Philadelphia, Pennsylvania, this 4th day of December, 1926.

WILLIAM J. BURNETT.
